US0D1005466S

(12) **United States Design Patent** (10) **Patent No.:** **US D1,005,466 S**
(45) **Date of Patent:** **** Nov. 21, 2023**

(54) **HUMIDIFIER**

(71) Applicant: **Shenzhen Miao Xin Technology Co., Ltd**, Guangdong (CN)

(72) Inventor: **Wenkai Zhang**, Guangdong (CN)

(73) Assignee: **Shenzhen Miao Xin Technology Co., Ltd**, Shenzhen (CN)

(**) Term: **15 Years**

(21) Appl. No.: **29/806,338**

(22) Filed: **Sep. 2, 2021**

(51) LOC (14) Cl. **23-04**

(52) U.S. Cl. **USPC D23/356**

(58) **Field of Classification Search**

(57) **CLAIM**

The ornamental design for a humidifier, as shown and described.

DESCRIPTION

FIG. 1 is a front, top perspective view of a humidifier showing my new design;

FIG. 2 is a rear, bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a partially enlarged view of FIG. 2.

The broken lines shown on the drawings depict portions of the humidifier that form no part of the claimed design. The broken lines encircling portions of the humidifier in FIGS. 2 and 9 depict bounds of the enlargement that form no part of the claimed design.

1 Claim, 9 Drawing Sheets
